UNITED STATES PATENT OFFICE.

DANIEL V. FORSBERG, OF LAUREL, NEBRASKA.

RIDING-CULTIVATOR.

SPECIFICATION forming part of Letters Patent No. 651,707, dated June 12, 1900.

Application filed March 8, 1900. Serial No. 7,855. (No model.)

To all whom it may concern:

Be it known that I, DANIEL V. FORSBERG, a citizen of the United States, and a resident of Laurel, in the county of Cedar and State 5 of Nebraska, have invented a new and Improved Riding-Cultivator, of which the following is a full, clear, and exact description.

One purpose of my invention is to so construct a riding-cultivator that each shovel-beam may be quickly and conveniently adjusted by the hands of the rider either in a lateral or sidewise direction or raised and lowered at their rear ends.

A further purpose of the invention is to so 15 construct a riding-cultivator that the shovel-beams may be vertically adjusted at their forward ends and held in adjusted position, enabling the beams to be so set that the shovels will enter the ground to a greater or 20 a less extent.

Another purpose of the invention is to accomplish the above-mentioned purposes by means of simple yet durable and economic construction.

25 The invention consists in the novel construction and combination of the several parts, as will be hereinafter fully set forth, and pointed out in the claims.

Reference is to be had to the accompanying 30 drawing, forming a part of this specification, in which is represented a perspective view of a riding-cultivator embodying the features of my invention.

As shown, the frame A consists of side bars 35 10, a front bar 11, and a rear bar 12, the latter supporting a seat 13. The tongue or pole 14 and its braces 15 are secured in any desired manner to the front bar 11 of the frame, and the axle 16 is preferably a crank-axle, 40 having the usual supporting-wheels 17 loosely mounted on its spindles. An opening 18 is made in the front cross-bar 11 of the frame at each side of the center, and these openings extend through the front edge of the said 45 cross-bar, but are normally closed by straps 19, so that by removing the straps articles contained in the openings 18 may be readily taken out. An upper or auxiliary cross-bar 20 is pivotally attached to the main front 50 cross-bar 11 of the frame A through the medium of a pivot-pin 21, which admits of the

auxiliary cross-bar 20 being raised and lowered. The auxiliary cross-bar 20, which is an adjusting-bar, as will be hereinafter shown, is provided at each side of its center with a 55 slot 22 in its forward edge, and these slots register with the openings 18 in the main front cross-bar 11. Wear-plates 23 are secured upon the upper face of the adjusting-bar 20, the said plates 23 having slots corresponding to the slots 22 in the bar, and the said adjusting-bar is raised or lowered by means of set-screws 24 or their equivalents, which are passed through the end portions of the adjusting-bar to a bearing upon the 60 upper face of the front main cross-bar 11 of the frame.

The beams B are provided with any suitable form of shovels C, and the forward ends of the beams B preferably have straps 25 secured thereto, and the straps of each shovel-beam are pivotally attached to the bottom portion of a shaft 26. These shafts 26 are passed loosely upward through the openings 18 in the frame and the slots 22 in the adjusting-bar and are supported by pins 27, which extend from their sides or are passed through them, which pins have bearing upon the wear-plates 23 on the adjusting-bar. The shafts 26 are preferably hollow and are 65 guided near their lower ends, where they are passed through eyes 28, formed on arms 29, extending usually from the tongue or pole 14. The shafts 26 may be adjusted vertically, and consequently the forward ends of the 70 beams may be raised or lowered, and thus control the depth to which the shovels shall enter the ground.

A handle 30 is connected with the upper portion of each shaft 26. These handles are 75 within easy reach from the driver's seat 13 and are usually provided with forks 31 at their forward ends, which forks receive the upper ends of the shafts 26 and are pivotally attached to said shafts. Thus by moving the 80 handles 30 to the right or to the left the shovel-beams will be moved sidewise in a desired direction. Furthermore, the rear end of either shovel-beam may be raised or lowered for any purpose by simply pressing down upon the 85 rear ends of the handles 30, as the forked portions of the handles 30 are connected by links 90.

32 with the shovel-beams at a point near the connection of said beams with the adjustable shafts 26. The links 32 pass downward through slots made longitudinally in the 5 shafts 26 and are attached to the shovel-beams by pivot-pins 33.

A vertical adjustment is given to the forward portions of the shovel-beams B by manipulating the set-screws 24, since as the adjusting-bar 20 is raised or lowered the shafts 26 will be moved correspondingly, as the said shafts rest upon the adjusting-bar. Any desired form of braces 34 may be employed at any portion of the frame.

15 Having thus described my invention, I claim as new and desire to secure by Letters Patent—

1. In a riding-cultivator, a frame, vertical shafts mounted to slide vertically and turn in 20 the said frame, means for vertically adjusting the shafts in the frame, handles attached to said shafts, and shovel-beams pivotally attached to the said shafts, for the purpose specified.

25 2. In a riding-cultivator, a frame, shafts having vertical movement in the frame and likewise rotary movement, handles pivotally attached to the upper portions of the shafts, shovel-beams pivotally connected with the 30 rear portions of the shafts, and a connection between the forward ends of the shovel-beams and handles for lifting the rear ends of the said beams, as set forth.

3. In a riding-cultivator, the combination, 35 with a frame, shovels mounted to slide vertically in the said frame, said shafts having likewise rotary movement in the frame, handles pivotally attached to the upper portions of the shafts, extending in a rearward and 40 forward direction therefrom, shovel-beams pivotally attached to the bottom portions of the said shafts, and links pivoted to the forward portion of the handles and to the shovel-

beams near their pivotal connection with the shafts, as specified.

4. In a riding-cultivator, the combination, 45 with a frame, an adjusting-bar carried by said frame, means for raising and lowering the said bar, shafts having vertical and rotary movement in the frame and in the adjusting-bar, and projections from the shafts, which projections rest upon the adjusting-bar, of handles pivoted to the upper ends of the shafts, extending rearward and forward therefrom, shovel-beams pivoted to the bottom portion of the said shafts, and links pivotally connecting the forward ends of the handles with the forward portions of the shovel-beams, for the purpose specified.

5. In a riding-cultivator, the combination 50 with the frame, of a vertically-adjustable bar on the frame, vertical shafts passing loosely through the said bar and frame, said shafts being supported by said bar, shovel-beams pivoted to the lower ends of the shafts, and 55 handles secured to the upper ends of the shafts, substantially as described.

6. In a riding-cultivator, the combination 60 with a frame, of vertical shafts mounted to slide and turn in the frame, said shafts being 70 longitudinally slotted, shovel-beams pivoted to the lower ends of the shafts, handles pivoted between its ends to the upper ends of the shafts, and links pivoted to one end of the handles passing down through the slots 75 of the shafts and having their lower ends pivoted to the forward ends of the shovel-beams, substantially as described.

In testimony whereof I have signed my name to this specification in the presence of 80 two subscribing witnesses.

DANIEL V. FORSEBERG.
